ATOMIZER

Harold E. Curry, Santurce, Puerto Rico

Application August 29, 1955, Serial No. 37,684

Term of patent 14 years

(Cl. D83—1)

Fig. 1

Fig. 2

Fig. 3

Fig. 1 is a perspective view of an atomizer showing my new design.

Fig. 2 is a top plan view of same.

Fig. 3 is a rear elevation of the same. The bulb and stem are omitted for convenience of illustration.

The dominant features of my design are shown in full lines.

I claim:

The ornamental design for an atomizer, as shown and described.
